UNITED STATES PATENT OFFICE

GEORGE E. SANFORD, ERNST W. KOPKE, AND HENRY E. PROCUNIER, OF CHICAGO, ILLINOIS, ASSIGNORS TO INTERNATIONAL CLARIFYING COMPANY, OF CHICAGO, ILLINOIS, A CORPORATION OF NEW JERSEY.

CENTRIFUGAL SEPARATOR.

984,242.

Specification of Letters Patent. Patented Feb. 14, 1911.

Application filed February 28, 1910. Serial No. 546,568.

To all whom it may concern:

Be it known that we, GEORGE E. SANFORD, ERNST W. KOPKE, and HENRY E. PROCUNIER, citizens of the United States, residing 5 at Chicago, in the county of Cook and State of Illinois, have invented new and useful Improvements in Centrifugal Separators, of which the following is a specification, reference being had to the accompanying drawings, forming a part thereof.

This invention is an improvement upon the centrifugal separator shown and described in our joint application, Serial No. 534,806, filed December 24, 1909.

15 It consists in the features of construction shown and described as indicated in the claims.

20 In the drawings:—Figure 1 is a vertical axial section of a structure embodying this invention. Fig. 2 is a front elevation of the same on a reduced scale. Fig. 3 is a side elevation of the same, showing the top swung back for removing or inserting the bowl. Fig. 4 is a section at the line 4—4 on Fig. 1.

25 The specific purposes of the improvements shown in this application over and above that shown in our former application are to facilitate the insertion and removal of the centrifugal bowl, and also to facilitate the 30 removal and insertion of the shelves or flanges upon which the solid material is deposited in the bowl for the purpose of making it easier to discharge such accumulations and to cleanse the bowl.

35 The parts of the structure which are substantially the same as in our former application will not be described, except in general terms.

The apparatus comprises a hollow fixed 40 base, having at the center an upstanding hollow boss, 1^a, whose upwardly open cavity affords a seat and whose bottom forms a step bearing or support for the base, 2^a, of the standard, 2, of the turbine casing, said 45 standard comprising arms diverging upwardly from the base and joined at their upper ends by an annular flange or rim, 2^b, on which the turbine casing, 3, is lodged with its axis coincident with that of the base standard. The base, 2^a, is positioned in the 50 hollow boss between cushions, 4 and 4^a, as fully described in our said application. The usual construction of the turbine is shown and need not be particularly described. The

turbine shaft, 5, is stepped at its lower end 55 by means of a ball bearing formed in the upper end of the hub or central element, 2^c, of the standard 2. The upper member of the ball race is formed by means of a collar, 6, fast on the lower end of the shaft, 5, and the lower member of said ball race is formed by an annular element, 7, lodged in said hub. The ball seats in both members of the ball race are substantially conformed to the balls as to their curvature in planes radial to the 65 axis,—that is, with the radius substantially equal to the radius of the balls,—and the two seats viewed in radial section are at opposite ends of the diameter of the balls which is inclined at an angle of about forty 70 five degrees to the axis, each seat extending for substantially ninety degree of the circumference of the balls, so that the down thrust of the weight operates upon the balls at substantially their vertical axis, thereby 75 causing the minimum wedging action upon the balls.

On the upper side of the turbine casing, 3, there is mounted a shaft bearing standard or spider, 7, having its hub, 7^a, at the upper 80 end formed with an upwardly open chamber which accommodates the ball bearing, 8, for the turbine shaft, 6^a. Above this ball bearing, there is fast on the shaft a collar, 9, whose flange, 9^a, forms a cover for the ball 85 chamber. The turbine shaft projects above this collar, and at its upper end is secured rigidly to a cap, 10, whose upper end is exteriorly tapered and whose lower end carries a brake wheel 10^a, which coöperates 90 with a brake strap, 11, operated by a bell crank lever, 12, which is fulcrumed on the spider, as more particularly described in our said former application.

Upon the upper tapered end of the cap, 95 10, of the shaft, 5, the separator bowl is mounted. Said bowl comprises the bottom, consisting of two central elements, 12 and 13, clamped upon the inner circumference 100 of an annular element, 14, as more particularly described in our said former application, the cylindrical element or wall of the bowl, 15, being riveted upon the outer periphery of said annular element, 14. The central element of the bowl comprises a tubular axial part, 16, which is connected to the upper central element, 12, of the fixed bottom by means of a frusto-conical collar,

17, whose lower end is fitted about the upper end of said member, 12, of the bottom, and whose upper end is provided with a flange, 17^a, by which the part, 16, is secured to it 5 by bolts taking through the lowest annular shelf or ledge, 16^a, of said central member of the bowl, which has a plurality of similar shelves or ledges, 16^a, positioned at intervals in its height. The frusto-conical collar, 17, has a plurality of apertures, 17^b, between which are provided projecting outwardly a like plurality of blades or vanes, 17^c, for accelerating the communication to the liquor of the rotary movement of the 10 bowl for the purpose of the centrifugal separating action desired. The outer cylindrical element or shell, 15, of the bowl has interiorly projecting annular shelves or ledges, 15^a, corresponding in position to the shelves or ledges, 16^a, of the central member 15 of the bowl; and the inner diameter of said annular shelves, 15^a, is less than the outer diameter of the shelves, 16^a, by a small amount, for the purpose of leaving between the corresponding shelves or ledges of the two members a narrow annular aperture, 18. The head or top, 15^b, of the shell or outer element, 15, of the bowl has a central aperture, 15^c, and the central element, 16, 20 has a flange, 16^c, which covers said aperture. From the flange, 16^c, a cylindrical flange, 16^b, projects upward a short distance, and just within said cylindrical flange the flange, 16^c, has a multiplicity of apertures, 35 16^d, for the discharge of the material upward for overflow outward over the upper edge of said cylindrical flange, 16^b, as hereinafter described.

The bowl and turbine are inclosed in an outer shell, 20, mounted upon the base, 1. This shell is divided at a plane oblique to the axis, and the upper member, 20^a, is hinged to the lower at the lowest side of said oblique plane for the purpose of adapting 40 the upper end portion, together with the parts mounted thereon hereinafter described, to be tipped back as a cover to uncover the upper end of the bowl to permit its ready removal. For the same purpose, 45 there is formed in the side of said outer shell, 20, a door, 20^b, hinged at one vertical edge for swinging horizontally to open the side of the shell for the entrance and exit of the bowl, said door occupying a sufficient portion of the circumference of the shell to 50 effect this purpose. Upon the upper member, 20^a, there is formed an exterior annular pocket or receptacle, 21, having a sloping annular top, 22, which may be made as a removable cover as illustrated; and a similarly sloping annular cap, 23, is connected to the upper member, 20^a, of the shell so that between said two sloping elements, 22 and 23, there is formed a downwardly sloping 55 passage from the central aperture of

said annular element, 23, into the annular receptacle or pocket, 21. For conducting the material delivered upward through the aperture, 15^c and the aperture 16^c, and over the edge of the cylindrical flange, 16^b, into the said inclined discharge passage, an annular conducting plate, 24, is provided mounted by means of the cylindrical flange, 24^a, on said cylindrical flange, 16^b, so that while revolving with the bowl, said plate, 24, may conduct the material outward for delivery into said inclined passage. Said deflecting plate, 24, is removable from the annular flange, 16^b, through the central aperture of the annular cover, 22, said annular cover having itself a removable cover, 25, which is itself centrally apertured to accommodate the upper receiving end 16^d of the central or inlet element of the bowl.

The operation of the separator thus far described is substantially the same for its principal purposes as that of the structure described in our said former application, and may be briefly described. The liquor to be treated is supplied through the inlet 16^d of the axial passage of the central element, 16, of the bowl, discharged centrifugally through the aperture, 17, between the accelerators, 17^c, the heavier solids being deposited between the shelves, 15^a, the lighter solids or float material being caught under the shelves, 16^a, while the clarified liquor of the intermediate density passes up through the annular apertures, 18, between the shelves of the outer and central elements respectively, additional deposits of solid material, light and heavy, being made under the several shelves as the liquor rises, said liquor passing out eventually at the top through the apertures 16^c, and being discharged centrifugally by the path indicated into the annular pocket or receptacle, 21, from whence it flows off through a spout, 21^a.

For convenience in removing the solid deposit and cleansing the bowl, the shelves, 15^a, are made in sectoral parts, preferably or most conveniently, about 120 degrees, each three such sectors making up a complete shelf, and these shelves are lodged at their outer circumference upon angle supports, 25, secured to the shell, 15.

For facilitating the acceleration of the liquor necessary for the proper centrifugal action desired, it is preferable to provide accelerating lips or flanges, 26, projecting from the shelves; and when the shelves are made in sectoral parts, as above described, these accelerating lips or flanges are most conveniently made by folding down the metal of each shelf at one radial edge.

In order to secure the sectoral members of the shelves suitable to each other at their inner edges where they lack support, and thereby cause them to operate substantially as if integral for carrying the load which 130

will be deposited upon them, clips, 27, may be provided, each consisting of a piece of metal folded upon itself and having one of its folds rifted, as shown at 27^a, the rift being of suitable width to accommodate the accelerating flange, 26, such clip being applied at the abutting edges of each two consecutive sectoral members of the shelf, the unrifted member of the clip passing in above to the two sectoral members, and the rifted member striding the depending accelerating flange and passing in below the two abutting sectors respectively. The accelerating flange, 26, thus retains the clip securely in its proper position over the abutting edges, and the clip itself bearing upon both sectoral parts at the upper side sustains both of them by its rifted member at the lower side.

We claim:

- 20 1. In a centrifugal separator, in combination with a rotatable bowl, a fixed shell with- in which the bowl is mounted for rotation, such shell having its upper part hinged at one side to the lower part for swinging upward and over therefrom, and an exterior annular receiving chamber mounted on said upper hinged member of the shell.
- 25 2. In a centrifugal separator, in combination with a rotatable bowl, a fixed shell with- in which the bowl is mounted for rotation, said shell being divided at an oblique plane and the upper member being hinged at one side to the lower member for swinging upward and over therefrom for opening the shell; an annular receptacle mounted upon the outer side of such upper hinged member, and an inclined annular conducting plate whose outer circumference makes junction with the upper edge of said upper member 40 of the shell, and which extends thence inward overhanging the bowl, and an annular conducting plate removably mounted on the bowl encompassing the upper discharge of the bowl, and overhanging said inclined annular conducting plate.
- 30 3. In a centrifugal separator, in combination with a rotatable bowl, a fixed shell with- in which the bowl is mounted for rotation, such shell being divided and its upper mem- 50 ber being hinged to its lower member at one side for swinging upward and over to open the shell; an annular receiving chamber mounted upon the outer side of said upper hinged member; an annular con- 55 ducting plate which is joined at its outer circumference to the upper end of the upper member of the shell, and which extends thence inward overhanging the bowl, and a cover for the said annular receptacle which 60 makes junction at its outer circumference with the outer wall of said annular recep- tacle, and which extends thence inward

overhanging said inclined annular conduct- ing plate.

4. In a centrifugal separator, a bowl comprising an inner and an outer member in- closing an annular chamber between them, the inner member having a plurality of an- nular shelves projecting outwardly, and the outer member having a like plurality of an- nular shelves projecting inwardly, said shelves on the two members being spaced apart to form narrow annular passages be- 65 tween them, said shelves of the outer mem- ber being made in sectoral parts abutting at their radial edges, the said outer member having ledges on its inner surface for sup- porting said members at their outer circum- ference, and clips which clasp the adjacent 70 edges of said sectoral members at their inner circumference lapping both said abut- 75 ting edges.

5. In a centrifugal separator, a bowl comprising an inner and an outer member, in- closing an annular chamber between them, the inner member having a plurality of an- nular shelves projecting outwardly, and the outer member having a like plurality of an- nular shelves projecting inwardly, said shelves on the two members being spaced apart to form narrow annular passages be- 85 tween them, said shelves of the outer mem- ber having vertically projecting flanges for accelerating the rotary movement of the liquid with said rotary element.

6. In a centrifugal separator, a bowl comprising an inner and an outer member in- closing an annular chamber between them, the inner member having a plurality of an- nular shelves projecting outwardly, and the outer member having a like plurality of an- nular shelves projecting inwardly, said shelves on the two members being spaced apart to form narrow annular passages be- 95 tween them, said shelves of the outer mem- ber being formed of sectoral parts abutting at their radial edges, each sectoral part hav- 100 ing a vertically projecting flange at one of said radial edges; ledges on the inner wall of the outer member for supporting said sec- toral parts at their outer circumference, and clips for clasping the inner circumferential edges of said members, having one member 105 of the clasp rifted to stride the flange.

In testimony whereof, we have hereunto 115 set our hands, at Chicago, Illinois, this 15th day of February, 1910.

GEORGE E. SANFORD.
ERNST W. KOPKE.
HENRY E. PROCUNIER.
